MOTION PICTURE MACHINE

Morris Scheinfeld, Philadelphia, Pa., assignor of one-fourth to Jacob Freedman, one-fourth to Gilmore Wooler, both of Philadelphia, Pa., and one-fourth to Elbert A. Carbin, Jr., Swarthmore, Pa.

Application January 2, 1930, Serial No. 417,951

6 Claims. (Cl. 88—17)

My invention relates to motion picture machines, and it relates more particularly to improved fire extinguishing means adapted to be mounted upon the reel magazines of such machines.

The principal object of my invention is to provide improved means adapted to be mounted upon motion picture machines, whereby, in the event of the film catching fire, as it frequently does 10 when exposed unduly to the heat from the lamp, the fire will be confined to the exposed portion of the film, and will be prevented from reaching the main body of the film contained within the magazines.

15 A further object of my invention is to provide a device adaptable for the purposes aforesaid, which will be simple, efficient, and certain in its action, which may be used on existing types of motion picture projection machines, and which 20 will not interfere with the expeditious threading of the film through the projection machine when the reels are changed.

The nature and characteristic features of my invention will be more readily understood from the 25 following description, taken in connection with the accompanying drawing forming part hereof, in which:

Figure 1 is a vertical central section of a device adapted to be mounted upon the reel magazines 30 of motion picture machines, said device embodying the main features of my present invention;

Fig. 2 is a top or plan view thereof, detached;

Fig. 3 is a transverse section taken on the line 3—3 of Fig. 1;

35 Fig. 4 is a transverse section taken on the line 4—4 of Fig. 1;

Fig. 5 is a top or plan view of a portion of the device, detached; and

40 Fig. 6 is an underneath plan view of another portion thereof.

It will, of course, be understood that the drawing and description herein contained are illustrative merely, and that various modifications and changes may be made in the structure shown and 45 described without departing from the spirit of my invention.

Referring to the drawing, in the particular embodiment of my invention therein shown, the device is contained within a housing comprising a 50 stationary portion 10, and a portion 11 movable with respect thereto, the movable portion preferably being hinged by means of a pin 12.

The movable portion 11 of the housing is normally maintained in the closed position by means 55 of a coil spring 13, mounted on the hinge pin 12.

The stationary portion 10 of the housing is secured, by means of a bracket 15, to the wall 14 of the magazine through which the film passes.

A plate member 16 is mounted within the housing in such position that the film passes adjacent thereto, but normally does not touch the same. 60

The film may be guided through the device by means of a plurality of rollers 17, which are journaled by means of spindles 18. The spindles 18 are mounted in the side walls of the portion 10 65 of the housing. The central portions of the rollers 17 are reduced in diameter, so that the film bears against said rollers only at the edges thereof.

The movable portion 11 of the housing also carries a movable plate member 19, which is impelled toward the film by means of springs 20. The plate member 19 is provided with extensions 21, in which the spindles 22 are mounted. 70

The spindles 22 serve as a means of journaling rollers 23, adapted to bear against the side portions of the film. The ends of the spindles 22 upon which the rollers 23 are mounted extend into slots 24 in the side walls of the portion 11 of the housing. 75

The rollers 17 are preferably provided in pairs at each end of the device, and the rollers 23 are so located as to bear upon the film 25 at a point between the points where the film is supported by the rollers 17. 80

By the foregoing arrangement, when the film 25 is under normal tension, the plate member 19 will be held away from the plate member 16, and out of engagement with the film 25 where the same passes between said plate members, thus permitting the film to pass freely through the 90 device without having the picture surface thereof scratched.

The operation of the device may now be explained. When it is desired to insert a new film in the machine, the movable portion 11 of the 95 housing, and the parts carried thereby, are pulled away from the stationary portion 10 thereof, to the position shown in dotted lines in Fig. 1 of the drawing, whereupon the end of the film may be inserted in the device, it being noted that the bracket member 15 is provided with an open throat 26 on one side thereof to permit the film to be thus inserted. 100

The movable portion 11 of the housing, and the parts carried thereby, are now permitted to 105 swing to the closed position under tension of the spring 13, whereupon, by reason of the rollers 23 engaging the film 25, the plate member 19 will be retracted as the movable portion 11 of the housing is swung to the closed position. 110

However, in the event of the film catching fire, as soon as the same burns sufficiently to relieve the tension on the film, the springs 20 will cause the plate member 19 to be advanced toward the plate member 16, engaging the film therebetween. The film will thus be held between two metallic plates, and the fire thereby quenched, and prevented from reaching the main body of the film within the magazine.

10 It will be noted that the device is so constructed and arranged as to require no attention on the part of the operator, the parts automatically adjusting themselves to the proper positions. It will also be noted that during the normal operation 15 of the motion picture machine, the picture bearing portion of the film will pass through the device without bearing upon any portion thereof, so that there will be no resultant scratching of said picture bearing portion of the film.

20 I claim:

1. A fire extinguishing device for motion picture machines comprising a housing through which the film normally passes, a stationary plate mounted within said housing, a movable plate 25 arranged adjacent the stationary plate and adapted when released to hold the film against the stationary plate, means for guiding the film between said plates, means impelling the movable plate toward the stationary plate, and means for holding said movable plate separated from said stationary plate while the film is passing normally therebetween, said means comprising members carried by extensions of the movable plate and bearing against unsupported portions of the 30 film.

2. A fire extinguishing device for motion picture machines comprising a housing through which the film normally passes, a stationary plate mounted within said housing, a movable plate 40 arranged adjacent the stationary plate and adapted when released to hold the film against the stationary plate, rollers for guiding the film between said plates, means impelling the movable plate toward the stationary plate, and means for holding said movable plate separated from said stationary plate while the film is passing normally therebetween, said means comprising rollers carried by extensions of the movable plate and bearing against unsupported portions of the 45 film.

50 3. A fire extinguishing device for motion picture machines comprising a housing through which the film normally passes, said housing comprising two portions, one of which is movable with respect to the other, means for normally holding 55 the movable portion of the housing in its closed position, a stationary plate mounted within said housing, a movable plate arranged adjacent the stationary plate and adapted when released to hold the film against the stationary plate, said

60

movable plate being carried by the movable portion of the housing, film supporting members for guiding the film between said plates, means impelling the movable plate toward the stationary plate, and members bearing against the film between the film supporting members thereby to hold the movable plate separated from the stationary plate while the film is passing normally therebetween.

80

4. A fire extinguishing device for motion picture machines comprising a housing through which the film normally passes, said housing comprising two portions, one of which is movable with respect to the other, means for normally holding the movable portion of the housing in its closed position, a stationary plate mounted within said housing, a movable plate arranged adjacent the stationary plate, said movable plate being carried by the movable portion of the housing, means for guiding the film between said plates, means impelling the movable plate toward the stationary plate, and means for holding said movable plate separated from said stationary plate while the film is passing normally therebetween, said means comprising members carried by the movable plate and bearing against unsupported portions of the film.

85

5. A fire extinguishing device for motion picture machines comprising a housing through which the film normally passes, said housing comprising two portions, one of which is movable with respect to the other, means for normally holding the movable portion of the housing in its closed position, a stationary plate mounted within said housing, a movable plate arranged adjacent the stationary plate, said movable plate being carried by the movable portion of the housing, rollers for guiding the film between said plates, means impelling the movable plate toward the stationary plate, and means for holding said movable plate separated from said stationary plate while the film is passing normally therebetween, said means comprising rollers carried by extensions of the movable plate and bearing against unsupported portions of the film.

90

6. A fire extinguishing device for motion picture machines comprising a stationary plate, a movable plate arranged adjacent thereto and adapted when released to bear against the film and hold the same against the stationary plate, film supporting members immediately adjacent said plates for guiding the film between said plates, spring means impelling the movable plate toward the stationary plate, and members bearing against the film between the film supporting members thereby to hold the movable plate separated from the stationary plate while the film is passing normally therebetween.
